UNITED STATES PATENT OFFICE.

EDWARD B. WARREN, OF GARNET, MONTANA.

SHIPPING-CARTON.

1,318,628.

Specification of Letters Patent.

Patented Oct. 14, 1919.

Application filed October 5, 1917. Serial No. 194,941.

To all whom it may concern:

Be it known that I, EDWARD B. WARREN, a citizen of the United States, and a resident of Garnet, in the county of Granite and State of Montana, have invented certain new and useful Improvements in Shipping-Cartons, of which the following is a specification.

This invention relates to shipping containers or cartons and more particularly to an improved construction whereby the carton will be held closed without the use of binding cord or fastening string.

The principal object of the invention is to provide a carton having fastening means whereby merchandise packed in the box or carton and placed in transit will be assured against accidental opening, damage to the carton, or gaping of the cover attached to the same.

The invention further aims to provide a novel fastening means for connecting the body and cover portions of the carton in rigidly closed form while, at the same time, permitting the same to be easily opened when desired.

Another object of the invention is to provide a carton of this character for use by merchants and dealers requiring a strong container for merchandise to be shipped without the use of binding cord so that persons handling the container will be obliged to grasp the body thereof with the hands, as distinguished from the usual method of lifting a container by the binding cord attached to the same.

With these and other objects in view which will be apparent, from a consideration of the following description of the preferred embodiment of the invention, and a comparison of the accompanying drawing, wherein:

Figure 1 is a perspective view of the carton constructed in accordance with my invention.

Fig. 2 is a bottom plan view of the same.

Fig. 3 is a section on the line 3—3 of Fig. 2.

Fig. 4 is a bottom plan view of a slightly modified form of the invention.

Fig. 5 is a section on the line 5—5 of Fig. 4.

Fig. 6 is a detail perspective view of one of the fastening elements.

55 Referring to the drawing, and particu-

larly to Figs. 1, 2, 3 and 6, the body or receptacle 1 is constructed of a size regulated according to the merchandise which is to be shipped and includes the end and side walls and the bottom 2. The cover 3 is constructed to snugly fit over and embrace the receptacle 1 and is of a depth sufficient to cause its marginal edges to lie flush with the bottom of the receptacle. The free longitudinal edges of the side walls of the cover 3, however, are provided with extensions forming flanges 4, which may be bent from the edges of the cover to overlap the bottom of the receptacle, as is shown to advantage in Fig. 3 of the drawing. Each end wall of the cover 3 is notched, as at 5, forming an open space in the ends of the cover for a purpose which will presently appear.

In Fig. 6 of the drawing I have shown a detail of one of the retaining members 6, which is preferably constructed from a blank piece of relatively thin material stamped to provide radiating tangs 7 and an eye-loop 8. Intermediate their ends, the tangs are bent at right angles and their terminals are sharpened to provide points so that the tangs may be conveniently inserted through the material from which the container is constructed and, when this is done, the ends of the tangs may be bent upon themselves and forced into tight engagement with the inner surfaces of the container to securely hold the loops 8 in position on the exterior of the container, one being arranged at each end thereof. The fastening elements 6 are arranged in a position that will cause the loops 8 to project through the notches 5 when the cover 3 is placed in position and to fasten the cover, I have provided the complementary fastening members 9, one of which is fastened to each end of the cover 3. Each complementary fastening member 9 includes the radiating tangs 10 similar in construction to the tangs 7 and an extended tongue 11 which may be bent to form a hook for engaging the loops 8, as clearly shown in Fig. 1 of the drawing. In this manner, the ends of the carton are securely held.

At uniformly spaced intervals on the flanges 4, I have provided other fastening elements 6, the tangs of which are fastened to the flanges, as above described. At adjacent points on the bottom of the receptacle, are mounted the complementary fastening elements 9, the tongues 11 of which engage

the loops 8 to hold the flanges in overlapped position at the bottom of the receptacle. It will be understood that the fastening devices are constructed of thin metal so that 5 the different parts may be easily bent to apply them to the carton and to connect the coacting parts together, and, for the same reason, it will be obvious that any number of the devices may be used as desired.

10 In Figs. 4 and 5, substantially the same construction is provided excepting that the overlapped flanges 4' are of greater width whereby their free marginal edges will contact when the cover is secured in position 15 on the receptacle and instead of fastening the two different types of fastening elements to the flanges and receptacle respectively, only the flanges are provided with the fastening elements, one being secured to one 20 flange 4' and the other to the corresponding flange 4'. The tongue 11' in this form extends over the meeting edges of the two flanges and hook into the loops 8' of the co-acting fastening elements to securely hold 25 the two flanges together and give rigidity to the carton when closed.

With the use of this method of fastening the receptacle and cover together, the common expedient of binding cord is eliminated 30 and the resulting tearing of the edges and corners of the carton is avoided. Furthermore, the fastening members being yieldable will permit them to be used continuously and no damage to the carton 35 itself will appear when the cover is removed.

When the carton is used on display stands for the purpose of displaying the contents of the carton or when arranged on 40 store shelves, the flanges or flaps may be folded inwardly and engaged with the inner surfaces of the carton so that they will be out of the way and so that the entire interior space may be occupied by the contents 45 which is to be displayed or exposed.

From the foregoing, it will be observed that a very simple carton fastener has been provided, the details of which embody the preferred form, I desire it to be understood,

Copies of this patent may be obtained for five cents each, by addressing the "Commissioner of Patents, Washington, D. C."

however, that slight changes may be made 50 in the details of construction without departing from the spirit of the invention or the scope of the claims hereunto appended.

What is claimed is:

1. A carton of the character described 55 comprising a receptacle and a cover therefor, the end of said cover having a notch in the free edge thereof to expose a portion of the receptacle, fastening elements secured to the end of the receptacle and adapted to lie in the notch when the cover is on the receptacle, and complementary fastening elements secured to the ends of the cover beyond the notch and extending into said notch to engage the said fastening elements on the receptacle, 60

2. A carton of the character described comprising a receptacle and a cover therefor, the said cover having its ends notched and its marginal edges provided with extensions, the latter being adapted for folding over the bottom of the said receptacle, fastening means attached to the ends of the receptacle and disposed in the said notches when the cover is applied to the receptacle, 70 co-acting fastening means carried by the ends of the receptacle and engaged by the said fastening means in the notches to hold the said ends of the receptacle and the container rigidly together, and means 75 mounted on the said extensions and the bottom of the said receptacle to co-act for retaining the extensions in overlapped position on the bottom of the said receptacle.

3. A carton of the character described 85 comprising a receptacle and a cover therefor, the latter having its longitudinal marginal edges provided with extensions bent to form flanges for overlapping the bottom of the receptacle, fastening elements carried by 90 the said extensions, and complementary fastening elements fastened to the bottom of the said receptacle and co-acting with the said first mentioned fastening elements to secure the said extensions to the bottom 95 of the said receptacle.

EDWARD B. WARREN.
